GUN RIFLING MACHINE

Andrew Raiche, Providence, R. I.

Application May 16, 1941, Serial No. 393,800

13 Claims. (CL. 90—28.1)

This invention relates to a machine for rifling the barrel of a gun.

The usual manner of rifling a gun consists in forcing the helical cutting tool through the barrel by means of a ram rod with difficulty being experienced in the removal of the chips which are cut by the action of the rifling tool. The rod which is utilized for ramming the tool through the barrel is of considerable length and force to be applied by transmission through this long rod is at times unsatisfactory.

One of the objects of this invention is to provide a machine whereby the long ram rod to the rifling tool is eliminated and force is applied directly to the tool.

Another object of the invention is to reduce the resistance which chips of considerable size have to the movement of a rifling cutter through a rifle barrel.

Another object of the invention is to provide an arrangement whereby the chip which is formed by the cutter is more readily cleared and removed from the barrel.

Another and more specific object of the invention is to reduce the chip which is formed into small parts and wash the chip out of the barrel ahead of the cutter.

Another object of the invention is to provide an arrangement whereby hydraulic means may be utilized for forcing the cutter through the barrel to be rifled.

With these and other objects in view, the invention consists of certain novel features of construction, as will be more fully described, and particularly pointed out in the appended claims.

In the accompanying drawings:

Fig. 1 is a side elevation illustrating the complete machine;

Fig. 2 is a plan view thereof;

Fig. 3 is a side view, partly in section, illustrating the clearing tool;

Fig. 4 is a sectional view illustrating a portion of the barrel, the cutter and clearing tools therein, and the cylinder for the transmission of hydraulic power;

Fig. 5 is a sectional view illustrating a means for moving the hydraulic plunger;

Fig. 6 is an elevation of the cutter;

Fig. 7 is a sectional view of the nut for engaging the threaded portion of the hydraulic plunger;

Fig. 8 is a fragmental detail, partly in section, illustrating the connection of the retracting handle for the hydraulic plunger;

Fig. 9 is an enlarged detail, illustrating the

shaping of the cutter and clearing tool in their relation one part to the other;

Fig. 10 is a modified arrangement of means for actuating the rifling tool.

- 5 In proceeding with this invention, I provide a short, helical cutting tool or broach and force this tool hydraulically through the bore of the rifle for cutting a helical groove therein, thus eliminating the use of a long ram rod for this purpose. The chips which are cut in forming the groove in the barrel are broken into small parts by a rotary clearing tool which engages the leading end of the cutting tool and are forced by the cutting tool ahead of them as the cutting 10 tool proceeds through the bore of the barrel. This clearing tool is hollow with clearance back of its end portion so that liquid may be forced through the tool and will wash the broken-up chips with the liquid out of the end of the barrel 15 into a suitable container. Thus, the resistance that the chips form to the cutting is materially reduced.

With reference to the drawings, 10 designates the bed plate of the machine upon which the several parts of the machine are mounted, including several supporting standards. The standard 11 is secured to the bed plate intermediate the ends thereof and consists of a casting providing a cylinder 12 which has an end plate 13 bolted thereto and provided with a boss 14 threaded as at 15 for the reception of the barrel 16 of a gun threaded as at 17 and engaging the threads 15 of the boss 14. A piston 20 in the cylinder 12 extends through the packing gland 21 of the cylinder 12 and through the bearing portion 22 (Fig. 5) of the standard 23 and also through the threaded jaws 24 and 25 (see Figs. 5 and 7) carried by this standard. Both of the jaws 24 are pivoted as at 26 on the standard and 20 may be swung to and from engaging position by means of handle 27 pivoted as at 28 and having a slot and pin connection 28'. The jaws are limited in open movement by stop pins 24' and 25'.

45 The piston 20 is reduced to provide a rod as at 30 at the portion which extends through the bearing 21 and is threaded as at 31 for the extent necessary for its stroke. The jaws 24 and 25 are threaded to act as a nut and will engage 50 or disengage this threaded portion 31. The portion 31 extends through another standard 32 which provides a support for one of the thrust ball bearings 34 of gear 33 which engages with a second thrust ball bearing 35 at the other side 55 of the gear. A key 36 carried by gear 33 ex-

tends into the keyway 37 in the threaded portion 31. Rotation is imparted to the plunger rod 30 by this gear 33 which is driven as seen more clearly in Fig. 2 by pinion 38 rotated through shaft 39 by worm gear 40 which is turned by worm 41, shaft 42, pulley 43, belt 44, pulley 45, and electrical motor 46 mounted upon the bed 10. The end of the plunger designated 47 is free from threads and is reduced as at 48 (Fig. 8) to receive a collar 49 held in place through washer 50 and nut 51 on threaded stud 52. This collar is provided with a pin 53 extending therefrom to enter a slot 54 in the handle lever 55 pivoted at 56 on standard 57 rising from the bed 10 of the machine.

The rifling tool shown in Fig. 6 by itself is designated generally 60 and consists of shank portion 61 and a cutting head 62 provided with helical channels 63 with cutting edges and a recess 64 at its end. In use, a tapered bushing 65 is positioned in the end of the barrel 16, which bushing has a cylindrical bore to snugly receive the shank 61 of the cutter. The bushing is recessed as at 66 in order to obtain a grip on it for removal. Some liquid, such as oil, is contained in the bore 67 of the cylinder 12 and may be supplied or drawn from this chamber 67 through the threaded opening 68 to which the conduit pipe is attached, which affords a means for supplying fluid to the chamber or withdrawing it from the chamber during time of changing work from a completed barrel to a fresh one. In operation after the barrel is screwed into the boss 14 of the plate 13, I cause engagement of the jaws 24 and 25 with the threaded portion of the plunger and then by rotating this plunger through operation of the motor 46 the piston is fed forwardly to force the cutter 60 ahead of it. Upon completion of the stroke with the cutter, the plunger is withdrawn by releasing the jaws 24 and 25 through handle 27 and withdrawing the plunger by means of the handle 55.

In some cases, instead of the arrangement shown in Fig. 4, I may provide a block 101 (see Fig. 10) having a chamber 102 therein with a bore 103 for the reception of the rifling cutting tool 60. The gun barrel 16 is threaded into the block at 104 to form a tight fit therewith. An entrance opening 105 is threaded and provides access for placing the rifling tool 60 into the bore 103. Plug 106 is threaded into this opening 105 to close the same and is provided with threaded stud 107 through a threaded bore 108 in the plug 106. A squared head 109 is used for turning the threaded stud for initial engagement with the rifling cutter 60 so as to mechanically start its cutting in the bore of the barrel. After starting the rifling tool mechanically, I then withdraw the stud and fill the chamber 102 with liquid and by applying pressure to the supply of liquid through conduit 110 controlled by valve 111, I may force the rifling tool hydraulically through the bore of the barrel to provide helical grooves therein.

In order to break up the material cut in forming the grooves by the rifling tool as the cutter advances and which is sometimes helical in formation and of substantial length, I provide a clearing tool, designated generally 70 (Fig. 3), consisting of a tubular shank portion 71 and a head 72. The shank portion has a bore 73 which communicates with the helically arranged slots 74 of the head by means of opening 75 and through the end of the head by openings 76.

The forward edges of these helical slots 74 are sharpened to present cutting edges.

The shank is mounted in a standard 77 by means of sealing rings 78 of such material as "neoprene" or the like. An annular recess 79 provides a chamber for the reception of fluid through connection 80 and some flexible supply line 81 threaded into the recess 82 which communicates with this chamber 79. An opening 83 in the shank forms communication between the bore 73 and chamber 79. This standard 77 is mounted upon a slideable carriage 84 arranged with suitable gibbs on the slide 84' for sliding movement parallel to the movement of the plunger 20. This carriage is urged toward the work by means of a weight 85 and cord 86 directed over pulley 87 and engaging the carriage as at 88. A latch 89 serves to hold the carriage in retracted position during loading of the work into the machine. The shank 71 of the clearing tool is slideable through spaced bearings 90 which are fixed to the slide 84'; and between these spaced bearings there is a pulley 91 which is keyed in a slot 92 of the shank so that upon rotation of the pulley 91 by means of belt 93, pulley 94, and electrical motor 95 on the bed plate 10, the clearing tool will be rotated.

After the work is loaded into the machine and prior to advancing of the broaching rifling tool 60, the carriage carrying the clearing tool is allowed to move to the right, as shown in Figs. 1 and 2, so that the head 72 of the clearing tool will enter the bore of the barrel and its end 72' will enter the recess 64 in the cutter, the weight 85 serving to maintain the clearing tool in this engagement. The flexible pipe 81 is sufficiently flexible so as to supply liquid wash through the channels mentioned to the clearer tool during the full length of reciprocation of the carriage by a pump, while the hydraulic means are used to force the cutter through the bore of the barrel to cause the rifling thereof. As the ship is formed by the cutter 60, the chip is broken into small parts by the rotation of the clearing tool 70. The fine chips are washed toward the end 96 of the barrel by the solution passed through the clearer tool and are collected in some suitable container. This washing solution may be utilized over again by removing the chips which it washes from the formation of the helical groove in the barrel.

By this arrangement the resistance to the forward movement of the cutter is materially reduced. The chip (see Fig. 9) designated generally 99 is broken or cut frequently so as to relieve the cutting edges 100 of the cutting tool as it advances, these chips being washed rearwardly through the channels 74 of the clearing tool.

I claim:

1. The combination with a rifling tool for cutting channels in the walls of a bore with the cutting portion of the tool being provided with spaced cutting edges, of fluid means for forcing said tool through the said bore, a clearing tool adapted to be positioned adjacent the said cutting portion and operable for severing the material raised from the walls of the bore by the said rifling tool during the advance thereof in forming cutting channels in the walls of the bore and means for actuating said clearing tool simultaneously with the actuation of said rifling tool.
2. In combination with a rifling tool, hydraulic means for forcing said rifling tool through the bore of the gun barrel to be rifled, means for severing the material raised from the walls of said

bore by said rifling tool adjacent to the cutting edge of the tool during the advance of said tool in the said bore comprising a clearing tool adapted to be positioned adjacent a cutting portion of said rifling tool to engage the said material as raised, and fluid means for removing the said severed material from the said walls.

3. A rifling machine comprising a support having means thereon for securing a gun barrel in position to be rifled, a rifling tool positioned in the gun barrel, a cylinder having an opening therein communicating with the bore of said gun barrel, fluid means in said cylinder and in said gun barrel engaging said tool for transmitting a force applied thereto to said tool, said tool having a shank which is substantially equal in dimension to said bore, and means for severing the material raised from the stock of the gun barrel being rifled.

4. A rifling machine comprising a support having means thereon for securing a gun barrel in position to be rifled, a rifling tool positioned in the gun barrel, a cylinder having an opening therein communicating with the bore of said gun barrel, fluid means in said cylinder and in said gun barrel engaging said tool for transmitting a force applied thereto to said tool, said tool having a shank which is substantially equal in dimension to said bore, means for severing the material raised from the stock of the gun barrel being rifled, and fluid means for removing said material from the said bore as severed from the stock of the gun barrel.

5. A rifling machine comprising a support having means thereon for securing a gun barrel in position to be rifled, a rifling tool having means thereon capable of cutting spiral channels in the walls of said bore, means for forcing said tool through the bore of said gun barrel, and means for severing the material raised from the stock of the walls as the said rifling tool is advanced in the said bore, comprising a rotatably mounted cutting tool of a size to be received in the said bore and with the cutting portion thereof positioned in juxtaposition to the cutting portion of said rifling tool, and means for maintaining said relationship between the cutting portion of said tools during the advance of the rifling tool through said bore.

6. A rifling machine comprising a support having means thereon for securing a gun barrel in position to be rifled, a rifling tool having means thereon capable of cutting helical channels in the walls of said bore, means for forcing said tool through the bore of said gun barrel, means for severing the material raised from the stock of the walls during the advance of said rifling tool in the said bore, comprising a rotatably mounted cutting tool of a size to be received in the said bore and with the cutting portion thereof in juxtaposition to the cutting portion of said rifling tool, means for maintaining said relationship between the cutting portion of said tools during the advance of the rifling tool through said bore, and grooves on the periphery of said cutting tool of a size to permit the passage of the said severed material.

7. A rifling machine comprising a support having means thereon for securing a gun barrel in position to be rifled, a rifling tool having means thereon capable of cutting helical channels in the walls of said bore, means for forcing said tool through the bore of said gun barrel, a cutting tool rotatably mounted and of a size to be received in the said bore and with the cutting portion

thereof in juxtaposition to the cutting portion of said rifling tool for severing the material raised from the stock of the walls of the said bore by said rifling tool during the advance thereof in said bore, means for maintaining said relationship between the cutting portions of said tools, said cutting tool having grooves in the periphery thereof of a size to permit the passage of the said severed material and a bore extending therethrough the passage of a fluid therein for lubricating the cutting portions of said tools and for flushing said portions of the said material as severed by said cutting tool.

8. A rifling machine comprising a support having means thereon for securing a gun barrel in position to be rifled, a rifling tool having means thereon capable of cutting helical channels in the walls of said bore, hydraulic means for forcing said tool through the bore of said gun barrel, and means for severing the material raised from the stock of the walls during the advance of said rifling tool in the said bore, comprising a rotatably mounted cutting tool of a size to be received in the said bore and with the cutting portion thereof in juxtaposition to the cutting portion of said rifling tool, and means for maintaining said relationship between the cutting portion of said tools during the advance of the rifling tool through said bore.

9. A rifling machine comprising a support having means thereon for securing a gun barrel in position to be rifled, a rifling tool having means thereon capable of cutting helical channels in the walls of said bore, hydraulic means for forcing a rifling tool through the bore of said gun barrel, a cutting tool rotatably mounted and of a size to be received in the said bore and with the cutting portion thereof in juxtaposition to the cutting portion of said rifling tool for severing the material raised from the stock of the walls of the said bore by said rifling tool during the advance thereof in said bore, means for maintaining said relationship between the cutting portions of said tools, said cutting tool having grooves on the periphery thereof of a size to permit the passage of the said severed material and a bore extending therethrough for the passage of a fluid therein for lubricating the cutting portions of said tools and for flushing said bore of the said material as severed by said cutting tool.

10. In a rifling machine a rifling tool, means for forcing said tool through the gun barrel to be rifled, severing means positioned in the bore of said gun barrel in close proximity to the cutting portion of the said rifling tool, for severing the material raised from the wall of the said bore by the rifling tool during the advance thereof in said bore, and means for maintaining the said relationship between the said severing means and the rifling tool during the rifling of said gun barrel.

11. A rifling machine comprising a support having means thereon for securing a gun barrel in position to be rifled, a rifling tool the shank of which is substantially equal in dimension to the bore of the gun barrel being rifled, a cylinder having an opening therein communicating with the bore of said gun barrel, a fluid means in said cylinder engaging said rifling tool for transmitting a force applied thereto to said tool, a plunger in said cylinder movable therein for transmitting a force applied thereto to move the fluid through the said bore to force said rifling tool through the bore of the gun barrel.

12. In a rifling machine the combination with

a rifling tool, the cutting portion of which is located at one end extremity thereof, of a rotary cutting tool adapted to be positioned in the bore of the gun to be rifled at a location in advance of the rifling tool and closely adjacent to the cutting edge of the rifling tool and operable for severing the material raised from the walls of the bore during the cutting of the channels therein by the rifling tool.

13. In a rifling machine, a tool adapted to be positioned in a bore, said tool having a shank and means thereon for cutting channels in the

walls of said bore, said tool including said shank being of a length substantially less than the depth of the bore acted on and said shank being of a diameter substantially equal to the said bore and forming the only guide for the tool through said bore, means for conducting fluid to said gun barrel to engage said shank, and means to place said fluid under pressure for acting directly on the end extremity of said shank for forcing said tool through said bore.

ANDREW RAICHE.
